Primary Examiner — Sandra Snapp(74) *Attorney, Agent, or Firm* — Erickson Kernell IP,
LLC(57) **CLAIM**

The ornamental design for an electronic massager, as shown and described.

DESCRIPTION

FIG. 1 a perspective view of an electronic massager showing my new design:

FIG. 2 is a front view thereof;

FIG. 3 is a left side view thereof;

FIG. 4 is a right side view thereof;

FIG. 5 is a top view thereof.

FIG. 6 is a bottom view thereof; and,

FIG. 7 is a back view thereof.

1 Claim, 5 Drawing Sheets(56)
